Margaret Gerrish of Salem, - Massachusetts -

Letters Patent.

The Schedule referred to in these Letters Patent, and making part of the same, containing a description in the words of the said Margaret Gerrish herself of her discovery, material in the fibres of the external and internal cortex of the *Asclepias Syriaca*, and the method of manufacturing the same, -

To all to whom these presents shall come,

Be it known that I, Margaret Gerrish of Salem in the County of Essex, and State of Massachusetts, have discovered a new and useful material in the fibres of the external and internal cortex of the *Asclepias Syriaca* and the following is a full and exact description of the said material as discovered by me, viz. It consists in a beautiful, plentiful long and strong fibre, and having been more or less engaged in making experiments upon the same and manufacturing it, altho upon a small scale, the five years past, the results have been such, I think, as to authorize the conclusion, that it will produce a fabric much superior in strength and beauty to linen - and one important advantage that it possesses over that article in common with cotton &c. is that it requires no bleaching. Very important when it is considered, that linen thread is said to lose by the operation of bleaching from one third to one fourth of its weight, besides the time, labor, and expense of bleaching. The substance also possesses the singular property of sustaining the repeated action of water uninjured and unweakened to a degree unknown in other similar substances and this is an advantage that it has over silk which is well known will not bear the same treatment, and it may be so prepared as to resemble silk when after it is spun, in some preparation, necessary - is being washed it resembles a moderately soft woolen yarn, in another

Margaret Gerrish

case where it has been longer subjected to the action of a solution of soap and washed after it is spun it resembles silk, and in some dressings it has somewhat the appearance of linen, and even cotton, so that the conclusion is, that by different preparations of the materials, different fabrics may be produced. And while it partakes in appearance of the properties of each of those materials it differs from all of them and is indeed a new material.

Some description of the plant *Asclepias Syriaca* -

This plant is a native of these States, and is thus described by Dr. C. M. Beglow, in his "Flora Bostonicasis." *Asclepias Syriaca* common silk weed or milk weed, very common by road sides and borders of fields. Stems three or four feet high undivided, leaves opposite, large strong, umbels of flowers lateral and terminal, nodding July. ^{September} Dr. C. M. Beglow, observes, as quoted into Dr. Thatcher's Descriptive, that this species of *Asclepias* rises from three feet to six, I have measured it five feet eight inches, and I have since seen some that could not have been less than seven feet, the flowers are of a pale purplish or pinkish hue, and remarkably sweet scented, the pods or follicles which may average six or eight upon a stem, contain from two to three hundred seeds each, which when fully ripened and the pods dried, they open into two parts, and the winged seeds are scattered by the wind. There appears to be a slight difference in the manner of its growth, while some of it rises up with a smooth round stem, others grow more of a square form, and not so smooth, but the round smooth stems are generally to be preferred, these have also fewer leaves, which makes the stripping of the bark easier and makes the bark break off in the fibers, among all the plants producing a thread like fiber, which I have met with I have observed none that are soaceous, to that degree that this is, it is, not the leatherbark common to most plants, but abounding

in a milk similar at least in appearance to a rich animal milk, like the veins of the cow, indeed approaching to veins in appearance, and which on breaking off the stems, or leaves, exudes most profusely, from which comparatively exclusive property no doubt this species is distinguished from the others by the name of Milk weed, as from the silken down contained in the follicles, it is also called in common with the other species, Silk weed, but which now from its promising importance should forever drop the name of weed, and be allowed to take that of plant, the fibres being nourished with this rich milk, doubtless acquire that glossy and silk-like appearance, which they possess in a high degree, I have not observed any thing of the kind in Linum but in unwinding the cocoon of the Bombyx, I have observed an adhesive gum,

Season of Cutting — —

The proper time for cutting, is when the plant is in full blow, which is in July, but in some seasons extends to August, at which time it is also in full milk and full fibre, — and the fibres are much more silk-like and beautiful at this period than at any other, and are much easier stripped from the exterior at this period, the cutting however, may be continued to September —

Process of preparing it to Manufacture —

When cut which should be even with the soil, take off the leaves, tops, and flowers, with a small knife, beginning at the lower part of the stem, dividing the exterior cortex, say, into four parts, which make a convenient width for stripping which done, it may be stripped piece by piece, generally the whole length of the stem; a considerable quantity may thus be stripped in a very short time after which, the fibres are to be separated from the bark, which is very easily affected, by cutting across the bark

1422.

bark and turning it back, with a small knife, when will instantly be perceived, the delicately white and glossy fibers beautifully arranged as it were for a web of cloth. which by taking hold of with the thumb and fore finger may be stripped out from two to four feet in length; The fibers thus stripped from the interior of the exterior cortex, may be laid along together carefully, lest they become entangled till a small parcel be acquired convenient for handling, when it may be tied together and thrown into pure water, where it may remain for days or weeks shifting the water occasionally. After which it may be thrown into a warm but weak solution of white or common soap, which separate the fibers from whatever of the green tannin bark, or milky particles which may still adhere to them, which leaves them perfectly white and soft, they may then be rinsed in pure water, and the same process repeated if necessary. Or it may be prepared by a cold process which in some cases, and for some purposes, is preferable to any other. But the most expeditious method of doing it is, to immerse it immediately into a warm solution of soap and raise the temperature if you wish to quicken the operation, It should be wrung out with care as the fibers are very delicate and being wet renders them liable to be broken. Squeeze it gently and open it a little ^{but} out when partly dry is the best time to open it effectually. It may then be rinsed in the sun or shade, but the sun is to be preferred, a time which it will require to be more opened - when it will be necessary to pass it through a fine comb but it is not always necessary to pass it through a comb, it may be sufficiently cleaned by hand for common purposes. It is then prepared for drying, however, I think from the experiments which I have made, that the fibers can be taken from the bark better after the bark has been stripped for two or three days, and that the bark can be easily given

3/27/1834 8111x

the skin equally well after the lapse of several days, or more, which may sometimes be found convenient. The process of preparation being extremely simple, as has been shown, so much so, that it comes within the means of the humblest peasant. No apparatus being necessary but a small knife, a tub or run of water -

2. The shorter fibres which remain in the comb, after combing may be again subjected to the action of a hot or boiling solution of soap, until the fibres be sufficiently broken up for carding, which when done makes a very light, delicate and almost transparent battling, which can be manufactured into a wadding particularly suitable for silk dresses, and which may be coloured to correspond to any required shade.

Spinning

After having been thus dressed it is fit for spinning, which is done upon the common linen wheel, with a slight alteration in the present construction of a part of that machine termed the distaff. In spinning this material there is much less to injure the eyes and lungs, than in cotton or flax, or coloring.

This material when manufactured into a thread, as above described, washed or boiled in a solution of soap, rinsed in fair water and slightly alumined is duly prepared to receive the coloring you may chose to give it. The attraction for coloring matter appears to be as strong and equal as that of silk, indeed it attracts the coloring, partially more equal than that material, if we may judge from the account of those acquainted with the business, and decidedly more than that of cotton or linen, which I should suppose a highly important object⁺ we are told that cotton and linen do not take blots like with resist soap; and that when intended to be dye'd, they must be subjected to the operation of scouring, alumining, and galting, and that the separation of silk with alum, is necessary in all cases while the nickelum Dye. att Dying.

3/27/1834 811X

Asclepias readily takes the coloring matter without even the alumining, as is the case of some of those specimens offered for inspection but then the alumining makes the color take deeper hold faster and appear brighter —

N. B. The *Asclepias Syriaca*, is said to be cultivated in Europe and in this country, for the silken down attached to the seeds, which is used as a substitute for fable, fur, and cotton. The tender sprouts are eaten in the spring for greens, and the "bark of the root of this species is also highly medicinal" it is said to be very pleasant to travel in the woods where it grows, especially in the evening, the flowers are so very odorous, and that in Canada they make sugar of them — gathering them in the morning when they are covered with dew. If sugar can be procured from the flowers, the value of the plant, will be greatly enhanced, because, the proper time for cutting the plant to manufacture into cloth, is when it is in full blossom which would be just the proper time for gathering the flowers to make sugar, which otherwise would be thrown away. — Comparative view of the culture and preparation of *Asclepias* with *linum* and *gossypium*

When we compare the culture of this plant and the preparations necessary to the manufacturing of it, with that of linum, or even cotton, we shall find I think, that the results are immensely in favor of the *Asclepias*, let us look our attention for a moment to the subject, transplanting it into a compact state, from the straggling state in which it is naturally found to grow, as all that would be necessary in the outset, or perhaps sowing the seeds — it would grow after that protégé itself, being a perennials or it would not require to be resown annually as flax does, and sowing it over with the seeds, as would be necessary, would just

it in proper order, I should suppose its natural soil being
the way side, by walls and hedges, and borders of deserted
plots and fields; the natural inference appears to be, that
any common soil is the most proper for it, we will suppose
it thus transplanted, and being well rooted and grown
to maturity, and in full blossom in full milk, and consequent
ly in full fiber, we have only to apply the sharp scythe
(a some similar instrument I supposed) and in a few
moments, thousands of their proud heads may be leveled
with the earth. When the simple process as before described
may be fully recited to. For flax we are told, that the
land must be ~~not~~ well tilled and laid
flat and even, then the seed are to be sown, and if a
wet season weeding will be necessary (and every two
or three crops, the, the seeds are to be renewed) and this
is to be repeated every year, when full grown it is to
be pulled, to be tied up, in handfuls, set up to dry and
when perfectly dried, hoosed, It is then to be washed
this process is said to be performed to the greatest adven-
tage in pits situated on the banks of rivers, where the
water may be changed often enough to prevent a degree
of putrefaction that would injure the flax, and be
injudicial to the workmen, After this process, it is again
to be hoosed and twice winnowed, and to pass through
two hobbles, But for the finest uses it is to be pulled
into rolls and put into a trough and scarcely beaten,
then opened and passed through the finest hobbles and
three different sized combs, Of the waste in dressing there
is no comparison, if required to be white it must be sub-
jected to the operation of bleaching. In cotton we are in-
formed, that the soil should be extremely well prepared
and of the best quality for the reception of cotton seeds
when ripe the pods are to be picked, and after the

hicks have been discovered the cotton is put to two only, one of a coarse operation than the other for separating the seeds from the cotton. But after this it is not completely freed from its seed, and other foreign matter. It is then carefully picked by Women and Children, The next operation of importance is the process of washing it with soap. It is then to be pressed, after pressing it is to be spread and brought to the stoves to be dried. It is next to be carded, and then passed through the drawing machine, as many times as may be necessary to obtain the required fineness, then through the roving machine after which it arrives at the spinning frame, and this article in common with linen, if required to be white, must be subjected to the operation of bleaching.

* Into thread, knitting, socks and various other articles some of which together with the material in its natural state, and in a prepared state for manufacturing have been presented as true specimens of the above described material and manufacture as discovered and manufactured by me
